United States Patent [19]
Caldeira

[11] Patent Number: Des. 291,021
[45] Date of Patent: ** Jul. 28, 1987

[54] POCKETED SHOE

[75] Inventor: Adelino Caldeira, Taunton, Mass.
[73] Assignee: Kangaroos U.S.A., Inc., St. Louis, Mo.

[**] Term: 14 Years

[21] Appl. No.: 617,226

[22] Filed: Jun. 4, 1984

[52] U.S. Cl. D2/309
[58] Field of Search D2/309-313;
36/113, 114, 115, 50, 136
